UNITED STATES PATENT OFFICE.

JOSEPH F. LAMB, OF NEW BRITAIN, CONNECTICUT, ASSIGNOR TO LANDERS, FRARY & CLARK, OF NEW BRITAIN, CONNECTICUT, A CORPORATION OF CONNECTICUT.

DESIGN FOR AN ELECTRIC COOKER.

49,708.

Specification for Design. Patented Sept. 26, 1916.

Application filed June 23, 1915. Serial No. 35,975. Term of patent 14 years.

To all whom it may concern:

Be it known that I, JOSEPH F. LAMB, a citizen of the United States, and a resident of New Britain, in the county of Hartford, State of Connecticut, have invented a new, original, and ornamental Design for an Electric Cooker, of which the following is a specification, reference being had to the accompanying drawing, forming part hereof.

The figure is a side elevation of an electric cooker, showing my new design.

I claim:

The ornamental design for an electric cooker, as shown.

JOSEPH F. LAMB.

Witnesses:

B. W. CLARK,
E. L. HOYLE.
